UNITED STATES PATENT OFFICE.

STEPHEN A. D. CLARK, OF ST. JOSEPH, MISSOURI.

COMBINED CHAIR AND BED.

SPECIFICATION forming part of Letters Patent No. 276,774, dated May 1, 1883.

Application filed June 10, 1882. (No model.)

To all whom it may concern:

Be it known that I, STEPHEN A. D. CLARK, of St. Joseph, in the county of Buchanan and State of Missouri, have invented a new and 5 Improved Combined Chair and Bed, of which the following is a full, clear, and exact description.

The object of my invention is to provide a new and improved chair, which can be adjusted in various positions and can be extended to be used as a bed.

Reference is to be had to the accompanying drawings, forming part of this specification, in which similar letters of reference indicate corresponding parts in all the figures.

Figure 1 is a rear elevation of my improved combined chair and bed. Fig. 2 is a longitudinal elevation of the same, showing it raised for use as a chair. Fig. 3 is a plan view of the 20 same, showing the same extended for use as a bed. Fig. 4 is a longitudinal elevation of the same, in this position parts being broken out and others shown in section. Fig. 5 is a detail perspective view of part of side rail, showing 25 a modification in construction.

Two standards or legs, A, of wood or metal, are secured and properly braced on a suitable base, B, and to the upper ends of these standards the side bars, C', of the seat-frame are pivoted. The 30 side bars, D', of the back frame are pivoted to the rear ends of the seat side bars, C', and the side bars, E', of the leg-rest frame are pivoted to the front ends of the seat side bars, C'. A foot-rest, F, projects outward from the upper surfaces of the lower end of the leg-rest frame. A quadrant-rack, G, projecting upward from the rear end of the seat side bar, C', and a quadrant-rack, H, projecting downward from the front end of the seat side bar, C', are preferably made integral, and one of these rack-frames is attached to each side bar, C'. These quadrant-racks may be made separate and independent of each other; but I prefer to make them integral, as this simplifies the construction and makes the chair more durable. A bar, I, is passed edgewise transversely and loosely through the side bars, D', of the back frame at such a height from the pivoted ends of the side bars, D', that it can pass in between 45 the teeth of the racks G. This bar I is pro-

vided at the ends with handles I', and with notches a in the lower edge and at the sides of the quadrant-racks G, which rod is pressed by a spring, J, attached to one side bar, D', and to the bar I in the direction toward that 55 side of the racks G at which the notches a are provided. The bar I is provided with longitudinal slots b, through which pins or studs d pass, which also pass through the side bars, D', of the back-rest. A bar, K, passes edge-wise and transversely through the standards or legs A in such a manner that its upper edge can pass in between the teeth of the quadrant-racks H. This bar K is provided with notches f in the upper edge at the sides of the racks H, 65 and is pressed in that direction toward which the notches fare from the racks H by a spring, L. The bar K is provided with handles K' at the ends. An arm, M, projects downward from the lower end of each back-rest side bar, 70 D', which arms are rigidly attached to these side bars, D'. Connecting-rods N are pivoted to the lower ends of the arms M, and to lugs or jaws O, projecting from the under sides of the side bars, E', of the leg-rest. A series of 75 headed pins or pegs, P, are driven about equidistant into the upper surfaces of the side bars, C', D', and E'. Cords Q pass around the pegs P and through the covering R at the edges of the same, and around rods S, held against the 80 under side of this covering at the edges by the cords Q. The upper ends of the cords Q are secured or fastened on a button, hook, cleat, or equivalent device, T, on the rear side of the top cross-piece of the chair-back, by means of 85 which cords Q the covering can be drawn as taut as may be desired. This covering is made of canvas or some other suitable strong similar material, and extends in one piece through all the sections of the chair. The rods S are provided with eyes or loops g at the ends of each section, as shown in Figs. 1 and 3. A bracket-arm, U, projects back from the cross-bar V, connecting the legs A, and a plate, U', is attached to the free end of this bracket-arm for 90 receiving a chamber or other suitable vessel. The covering R is provided at the rear part of the seat with an opening, W, which can be closed by a transverse truss, X, passed under the covering R and provided with apertures h 100

for securing it on the pegs P; or it can be secured by buckles or other suitable devices. The back, seat, leg-rests, standards A, and the base - rails are connected by suitable cross-bars Y.

Without departing from the spirit of my invention, rollers P' may be used in place of the pins P, around which rollers P' the cords Q pass. The rollers are contained in suitable recesses in the rails C', D', and E', as represented in Fig. 5.

The operation is as follows: The bar I, catching between the teeth of the racks G, locks the back and the leg rest (which are connected) in place, and the bar K, which catches between the teeth of the racks H, locks the seat in place. By pushing or pulling the bar I in the direction of the arrow a', Fig. 1, the notches a will be brought over the racks G, and the racks can pass through these notches without catching on the rod I, and the back of the chair can be swung in the direction of the arrow b' or in the inverse direction as much as may be desired. If the back is swung in the direction of the arrow b', the leg-rest will be raised in the direction of the arrow c', and vice versa. If the back is raised the leg-rest will be lowered. As soon as the bar I is released the spring J throws it in the inverse direction of the arrow a', and the back and leg-rest will be locked in position. The back can be lowered and the leg-rest raised until the back, seat, and leg - rest form a horizontal platform, as shown in Figs. 3 and 4, which can be used as a bed or operating table, or for similar purposes in sick-rooms and hospitals. If the bar K is pushed or pulled in the direction of the arrow a', the racks H will be released, and the

seat can be turned on its pivot and will be automatically locked in any desired position as soon as the bar K is released. If the patient wishes to relieve himself, the band X is removed and a chamber or other suitable vessel is placed on the plate U', directly below the opening W.

Dentists' and barbers' chairs can also be constructed in the manner described above.

Having thus fully described my invention, what I claim as new, and desire to secure by Letters Patent, is—

1. A seat-frame having its side bars, C' C', pivoted to standards A, in combination with a front leg-rest frame and a back frame, respectively, pivoted to the forward and rear ends of said seat - frame, as shown and described.

2. The combination, with the pivoted seat-frame having rack G, of the bar I, having notches a in the lower edge, and the slots b, the pins d, and the back-frame side bars, D', having holes for the pins, and the spring J, as shown and described.

3. The combination, with the bar K, having handles K' and rack H, of the back-frame side bars, D', having arms M, the pivoted rods N, and the side bars, E', having lugs O, as described.

4. The combination, with the covering R, of the eye-rod S, the bars C' D' E', having the pins P, the cords Q, and the chair-back cleat T, as described.

STEPHEN A. D. CLARK.
